UNITED STATES PATENT OFFICE

EMIL FAURE, OF PARIS, FRANCE

HYDRAULIC RAM

Application filed September 1, 1928, Serial No. 303,556, and in France September 15, 1927.

The present invention relates to the construction of hydraulic rams with multiple battery-pipes and consists in a particular arrangement of these apparatus allowing of giving them the mechanical and hydraulic working characteristics necessary for making them into industrial machines.

It may be recalled that these kind of rams are constituted by a certain number of battery-pipes which are like as many separate rams. By causing these rams to operate successively there is obtained a practically constant output, as with multiple piston pumps.

However, if each battery-pipe is merely arranged as if it were the case of a single ram, that is to say by employing one pipe for its realization, there is obtained an apparatus with a large number of pipes, not at all compact, but adapted to produce dangerous resonances or hammer shocks and for these reasons unsuited to an industrial application.

The device forming the subject of the present invention allows of overcoming these disadvantages. It consists in replacing the pipes by contiguous conduits forming a single block. Owing to the community of the walls of the various conduits, the expansions of these walls, due to the water hammer shocks, produce in their turn reactions upon the water in the adjacent conduits; consequently, on the one hand these walls are relieved by the support which they receive from the fluid in the other conduits and on the other hand the hydraulic working of the whole of the machine is regularized by the dependence existing between all the conduits.

This block may be placed inside a casing; it then serves as separating partition between the three hydraulic regions which every ram comprises, these being: the medium pressure region through which the liquid enters, the exhaust at low pressure, and the delivery at high pressure.

This casing is closed by a cover which can be arranged in such a way as to provide, together with the block of battery-pipes, a hydraulic capacity contributing by the elasticity of the water, to damp out the pulsations of the fluid delivered. The action of this

capacity may be supplemented by the deformations of elastic plates pressed against the blocks of battery-pipes; in this way there is produced in the ram itself the elastic reservoir necessary to the absorption of the pulsations of the liquid.

The device may be further supplemented by systems of pressure-limiting flap valves, due to which the thicknesses of the walls of the conduits can be reduced to the minimum, in order to reduce the dimensions of the block of battery-pipes and also in order to favour the reactions of the conduits upon one another through the intermediary of the walls.

In the subsequent description it will be convenient to employ the following terms:—

“Ram body” to designate the block of battery-pipes.

“Low pressure” to designate the region from which the exhaust takes place.

“Medium pressure” for the region containing the liquid to be transformed.

“High pressure” for the region into which the compressed fluid passes.

“Distributor” for the member common to the battery-pipes and controlling the successive operation.

Upon the accompanying drawing there are represented by way of examples two forms of construction of the invention.

Figure 1 is an axial section of a first form of construction.

Figure 2 is a part section of the ram body along a plane perpendicular to the axis.

Figures 3 and 4 represent in transverse sections different methods of construction of the conduits.

Figure 5 is an axial section of another form of construction, in which the ram is combined with a centrifugal pump wheel with the object of providing a high pressure pump.

In the multiple pipe ram represented in Figure 1, the ram body is constituted in two parts (1 and 2) suitably connected together and comprising conduits (3) placed all round the axis $\alpha\alpha'$ in a plane perpendicular to this axis and to the delivery nozzle (4).

The distributor (5) is mounted upon the

shaft (6) and acts with each battery-pipe like a three-way cock; for this purpose it comprises holes (7) through which the pipes communicate with the delivery nozzle (4) and notches (8) through which these pipes communicate with the low pressure (9). The casing (10) which encloses the ram body comprises the low pressure space (9) with exhaust pipe (11) and the medium pressure space (12) of the shape of a torus, into which the water supply pipe (13) delivers.

A cover (14) closes the casing and carries the delivery pipe (15).

This cover serves to hold the ram body in place by the intermediary of lugs or supports (16); its shape is substantially spherical, so as to realize with the ram body a capacity (17) of which the elasticity contributes to damp out the pulsations of the water. Flexible plates (18) separate the capacity (17) from the medium pressure (12) and assist in the damping out of the pulsations.

If, for example, an excess pressure is produced in the capacity (17), these plates are deformed, taking up the position a', b ; the volume of the capacity (17) is thus momentarily increased by the area $a b a'$ cross sectioned in Figure 1. Consequently there results a reduction of the variation of pressure, like in the air vessels of pumps.

However, it may be remarked that the volume $a b a'$ is obtained at the expense of the medium pressure space (12); there might then result therefrom pulsations in this region. In order to prevent them, elastic plates (19) are arranged, fixed to the ram body and separating the medium pressure (12) from the low pressure (9). In this way the pulsations in (12) may be carried into the space (9) by the deformation of the plates (19).

It is easy to see that in these conditions the damping out of the pulsations in the three regions (17, 12 and 9) is ensured.

In fact, any instantaneous variation of output in (17) has for effect a variation of opposite sense in the instantaneous output in (9), since the total output, which is that which passes into (12) has to remain constant.

If then this variation of output in (17) has accumulated in the space $a b a'$, it suffices for the plates (19) to be deformed, under the action of the variation of pressure resulting therefrom in (12), by a quantity $e f e'$ equal in volume to $a b a'$, in order that on the one hand there shall be no variation of volume in (12) and that on the other hand the variation of volume in (9) shall be equal and opposite to that which is produced in (17). In this way, the outputs in the pipes (11) and (15) will be constant, since the elastic plates absorb the irregularities of outputs due to the operation of the ram.

Holes (20) formed in each battery-pipe, in the vicinity of the down stream orifice of this

pipe allow possible communication of this conduit with the high pressure (17), when a water hammer blow is produced. These holes are normally closed by flaps or valves (21) which may be identical with those used in hydraulic machines or specially adapted to their utilization in multiple rams.

The operation of the apparatus is as follows:

The fluid to be transformed being brought in under medium pressure through the pipe (13) into the torus (12), passes into the conduits (3) of the ram body. The distributor (5) is given a movement or rotation by a motor driving the shaft (6). When a conduit (3) is in communication with the low pressure (9), through the slot (8), the fluid which it contains takes on an accelerated speed under the effect of the pressure in (12), which is greater than in (9). The distributor having turned through a given angle, the same conduit is then placed in communication through the orifice (7) with the high pressure at (4); the fluid loses its speed by reason of the pressure in (4) which is greater than that in (12). But this fall of speed is not instantaneous and a certain volume of water is thus introduced into the high pressure.

The flexible plates (18 and 19) as well as the masses of water in the capacities (9 and 17), which have likewise a certain elasticity, absorb the irregularities of output in such a way as to pass into the pipes (11 and 15) only constant outputs.

When a dangerous water hammer tends to occur, the flap valves (21) lift, which prevents the hammer shock from exceeding the delivery pressure to any appreciable extent.

Figure 2 is a section of a ram body along the line 2—2 of Figure 1. The conduits (3) have a curved general shape which is an involute of a circle. This curve has for object to give these conduits the maximum of length with a minimum of interference and to maintain the section of the channel and the thickness of the walls constant. This shape is changed only at the two ends where it is necessary above all to guide the water in a suitable way.

Figures 3 and 4 are examples of conduits in perpendicular sections.

In Figure 3, the conduits are provided by partitions (20') all formed together in the same part and by a flat plate (21) which is made to press upon these partitions.

In Figure 4, the two parts of the ram body are similar to one another, each comprising partitions (22 and 22'). By assembling the two parts in such a way as to make the partitions register, the conduits are delimited.

Curves $a b$ and $a' b'$ in Figures 3 and 4 show the deformation of the walls under the effect of a water hammer shock in any one conduit (3). It is seen that this deformation

results in diminishing the cross-section of the adjacent conduits (3' and 3''), which produces water hammer shocks in these channels, opposing that produced in (3) and thereby reducing the strain or fatigue of the walls. Moreover, in the conduit (3), a water hammer will be produced with slowing down of the speed, whereas in (3' and 3'') the hammer shocks take place with acceleration of speed which fact re-establishes to a certain extent the average value of the output of the whole of the apparatus.

Figure 5 represents a pump constituted by the combination of the multiple ram with a centrifugal wheel, the centrifugal wheel (23) itself furnishing the fluid at medium pressure by compressing the low pressure water. The pipes (11 and 13) of the preceding example are in this case unnecessary.

The wheel (23) is mounted upon the same shaft (6) as the distributor (5) and revolves in the interior of the casing (10) which already contains the ram body. Its angular setting is such that its suction takes place in the low pressure region (9) and that its delivery communicates with the medium pressure region (12).

The fluid drawn in enters by the pipe (24) into a torus (25) integral with the casing and it passes into the low pressure region (9) by way of a passage (26) traversing the medium pressure region (12). The operation of the device is exactly the same as in the preceding instance.

What I claim is:

1. In combination, a multiple battery-pipe hydraulic ram, with battery-pipes constituted by contiguous conduits forming a block and a low pressure chamber, a rotary distributor for the battery-pipes of ram, a centrifugal wheel on the shaft of the said distributor, a casing for the said wheel, passage means between the low pressure chamber and the casing of the centrifugal wheel.

2. In a hydraulic ram comprising more than two battery tubes, a low pressure chamber, a pipe for discharging the water of the said chamber, a high pressure chamber, a pipe for discharging the water of said second-mentioned chamber, a pressure-equalizing chamber, a pipe for supplying water under pressure to said last-mentioned chamber, a block between the said high and low pressure chambers, a central passage through the said block, in combination with a series of convergent passages or battery tubes communicating constantly with the pressure-equalizing chamber, and a rotating distributor successively connecting the said convergent passages with the central passage.

3. In a hydraulic ram comprising more than two battery tubes, a low pressure chamber, a pipe for discharging the water of the said chamber, a high pressure chamber, a pipe for discharging the water of said second-

mentioned chamber, a pressure-equalizing chamber, a pipe for supplying water under pressure to said last-mentioned chamber, a block between the high and low pressure chambers, formed by the juxtaposition of grooved plates adapted to form a series of convergent passages, battery tubes communicating constantly with the pressure-equalizing chamber, a central passage through said block, and a rotating distributor successively connecting said convergent passages with the central passage.

4. In a hydraulic ram comprising more than two battery tubes, a low pressure chamber, a pipe for discharging the water of said chamber, a high pressure chamber, a pipe for discharging the water of said second-mentioned chamber, a pressure-equalizing chamber, a pipe for supplying water under pressure to said last-mentioned chamber, a block between the high and low pressure chambers, a central passage through said block in communication with a series of convergent passages in the form of a developed circle communicating constantly with the pressure-equalizing chamber, and a rotating distributor successively connecting said convergent passages with the central passage.

5. In a hydraulic ram comprising more than two battery tubes, a low pressure chamber, a pipe for discharging the water of the said chamber, a high pressure chamber, a pipe for discharging the water of said second-mentioned chamber, a pressure-equalizing chamber, a pipe supplying water under pressure to said last-mentioned chamber, a flexible wall between the pressure-equalizing and low pressure chambers, a block between the high and low pressure chambers, a central passage through said block in combination with a series of convergent passages communicating constantly with the pressure-equalizing chamber, and a rotating distributor successively connecting said convergent passages with the central passage.

In testimony whereof I have signed this specification.

EMIL FAURE.
